UNITED STATES PATENT OFFICE.

WORTHINGTON BROWN, OF CHILlicothe, MO., ASSIGNOR, BY MESNE ASSIGNMENTS, TO EMERSON C. FELTON, OF CHICAGO, ILL.

BUSTLE.

SPECIFICATION forming part of Letters Patent No. 350,111, dated October 5, 1886.

Application filed March 27, 1885. Serial No. 160,317. (Model.)

To all whom it may concern:

Be it known that I, WORTHINGTON BROWN, a citizen of the United States, residing at Chillicothe, in the county of Livingston and State of Missouri, have invented certain new and useful Improvements in Bustles, of which the following is a specification.

My invention is a bustle consisting of a series of metallic forms arranged to constitute a metallic frame flattened at one or more sides and contracted at the ends, as fully set forth hereinafter, and as illustrated in the accompanying drawings, in which—

Figure 1 is a perspective view of my improved bustle, showing one form in which it can be made. Figs. 2 and 3 are cross-sectional views, one near the center and the other near the end. Fig. 4 is a side view; Fig. 5, a view illustrating the position of the bustle upon the person of the wearer. Figs. 6 and 7 are sectional views illustrating modifications. Fig. 8 is a side view illustrating another modification. Fig. 9 is a perspective view illustrating another modification.

The bustle consists of a series of wire forms, *a*, arranged side by side and gradually diminishing in size toward each end of the bustle, and so connected together as to be retained relatively in place. These forms may consist 30 each of a separate wire or strip bent to the proper shape and secured to a connecting-strip, *b*, as shown in Fig. 9. I prefer, however, in most instances, to make all the forms from a single strip of wire bent to constitute a continuous wire frame somewhat like an ordinary spiral spring, but different from the latter in the shape and varying size of the spirals, as shown in Figs. 1 to 7.

The forms *a*, whether consisting of separate pieces or made from one continuous strip, are preferably flat upon one or two sides, as at *C*. Figs. 2, 3, 6, and 7, and curved upon another side, *d*. When there are two flattened sides, as in Figs. 2 and 3, each form is of approximately a triangular shape. When there is but one side flattened, as in Figs. 6 and 7, the form approximates a semicircular shape.

I have referred to the sides being flattened. They need not be absolutely straight, however,

but may be in some instances curved inward, so as to fit better the person of the wearer.

The bustle is provided with tapes or straps *G*, extending from the ends, so that they may be drawn around the waist and tied or otherwise secured; and these tapes or straps 55 may consist of a single piece extending through the bustle-frame or connected to the ends thereof.

In order to aid in securing the bustle to the body without causing it to bind too tightly, and without separating the coils to too great an extent, I in some instances extend through the frame an elastic band or spring, *F*, which may be made of any suitable material, a band being shown in Fig. 1, and a metal spiral spring 65 in Fig. 8, the latter figure also showing the bustle-frame as being composed of two series of forms made by arranging in juxtaposition two coiled wires of approximately the same shape, thus giving greater stiffness to the article.

The bustle thus constructed when applied to the body below or at the waist, substantially in the position shown in Fig. 5, serves to project the dress of the wearer and support the 75 same in its position, while at the same time it is yielding, so as to not cause discomfort to the wearer when seated or leaning against a stationary object. It will also be seen that a bustle of this construction is light in weight, not 80 liable to get soiled or to injure the clothing, and that it can be cheaply manufactured.

When it is desired to throw the bustle farther from the body or give a greater pitch to the clothing, the fastening tapes or bands *G* may 85 be connected to the frame at the corners *x*, which causes the frame to occupy a different position upon the body and produce the desired effect. In some instances the wire may be coated or covered with thread, or the entire 90 frame may be inclosed in a fabric covering.

The wire of which the frame is composed may be ordinary round wire or flat strips.

Without limiting myself to the precise construction and arrangement of parts shown and 95 described, I claim—

1. A bustle consisting of a series of forms of an approximate triangular shape, each form

constructed of wire and slightly curved inwardly at one or more sides and outwardly curved at the other, and all flexibly connected together to form a frame diminishing in thickness from the center toward the ends, substantially as and for the purpose set forth.

2. A bustle consisting of a frame composed of wire bent to form coils of an approximate triangular shape, flexibly connected together, and constituting a flexible frame diminishing

in size from the center toward each end, substantially as and for the purpose set forth.

In testimony whereof I have signed my name to this specification in the presence of two subscribing witnesses.

WORTHINGTON BROWN.
